UNITED STATES PATENT OFFICE.

CHARLES H. COWAN, OF STONINGTON, CONNECTICUT, ASSIGNOR TO THE ATWOOD-MORRISON COMPANY, OF STONINGTON, CONNECTICUT, A CORPORATION OF NEW JERSEY.

THREAD-GUIDE.

SPECIFICATION forming part of Letters Patent No. 783,683, dated February 28, 1905.

Application filed December 15, 1903. Serial No. 185,268.

To all whom it may concern:

Be it known that I, CHARLES H. COWAN, a citizen of the United States, and a resident of Stonington, in the county of New London and State of Connecticut, have invented a new and useful Improvement in Thread - Guides, of which the following is a specification.

My invention relates to an improvement in thread-guides; and it consists in a thread-guide which is reversible, so that when the thread-receiving groove in one side is worn down to a point where the free running of the thread is prevented the thread-guide may be reversed, and thus present a new thread - receiving groove in position for use.

My invention further consists in a reversible thread-guide having thread - receiving grooves in two of its opposite sides, the said thread-guide being also formed on these sides to engage either the spring guide-wire or the reciprocating guide-bar.

Practical embodiments of my invention are represented in the accompanying drawings, in which—

Figure 1 represents in front elevation a portion of the reciprocating guide-bar of a winding or reeling machine, together with two of my reversible thread-guides and the spring guide-wire for holding them in engagement with the bar. Fig. 2 is a transverse section through the guide-bar, showing one of the thread-guides in end elevation. Fig. 3 is a transverse section through the guide-bar and thread-guide in the plane of the line A A of Fig. 1. Fig. 4 represents in front view another form of reciprocating guide-bar and thread-guides. Fig. 5 is a transverse section through the guide-bar, showing the thread-guide in end elevation; and Fig. 6 is a transverse section through the guide-bar and thread-guide in the plane of the line B B of Fig. 4.

In the construction shown in Figs. 1, 2, and 3 the longitudinally-reciprocating guide-bar is denoted by 1 and the usual spring guide-wire for holding the thread-guides in position thereon by 2. The thread-guide, which may

be made of porcelain, glass, or other suitable material, is denoted by 3, and it is provided in two of its opposite sides with transverse thread-receiving grooves 4 and 5. This thread-guide is further provided in two of its opposite sides with longitudinal grooves 6 and 7, each of which is fitted to receive either the spring guide-wire or the reciprocating guide-bar, according to the position of the thread-guide. In the present instance I have shown the inner longitudinal groove 7 as receiving the tapered top 8 of the guide-bar and the longitudinal groove 6 as receiving one arm of the spring guide-wire 2.

In the form shown in Figs. 4, 5, and 6 the longitudinally-reciprocating guide-bar is denoted by 9, which guide-bar is provided with a longitudinal groove 10 in its top. The thread-guide in this form is provided with the transverse thread-receiving grooves 4 and 5, as in the form hereinbefore set forth. This thread-guide is further provided with longitudinal ribs 11 and 12, each of which is fitted to enter the longitudinal groove 10 in the guide-bar 9, according to the position of the thread-guide. These lugs 11 and 12 are provided with longitudinal grooves 13 14, each of which is fitted to receive one arm of the spring guide-wire 2, according to the position of the thread-guide.

When one of the transverse grooves in the thread-guide has been worn down to a point where it prevents the free running of the thread therethrough, the thread-guide may be immediately reversed to present a new transverse thread-receiving groove in position for use, thus materially lengthening the life of the thread-guide.

It is evident that the thread-guide may be made in various forms without departing from the spirit and scope of my invention. Hence I do not wish to limit myself strictly to the forms herein set forth; but

What I claim is—

1. A reversible thread-guide having transverse thread - receiving grooves in two of its

opposite sides and having the said sides also formed to engage either the guide-bar or guide-wire.

2. A reversible thread-guide having transverse thread-receiving grooves in two of its opposite sides and also longitudinal grooves in said two opposite sides for receiving either the spring guide-wire or the guide-bar.

In testimony that I claim the foregoing as my invention I have signed my name, in presence of two witnesses, this 14th day of November, 1903.

CHARLES H. COWAN.
